MOBILE DISPLAY CART

Melvin O. Maisak, Florissant, and William H. Fullington,
Ballwin, Mo., assignors to Pet Incorporated, St. Louis, Mo.

Filed June 11, 1969, Ser. No. 17,654

Term of patent 14 years

Int. Cl. D6—06; D12—02
U.S. Cl. D80—9

FIG. 4

FIG. 1 is a front perspective view taken from one end of a mobile display cart embodying our new design, FIG. 2 is a front elevational view thereof,

FIG. 3 is a cross-sectional view taken on line 3—3 of FIG. 2, and

FIG. 4 is an elevational view taken from the end opposite that shown in FIG. 1.

We claim:

The ornamental design for a mobile display cart, substantially as shown.
